LUMINAIRE

Mitchell Bobrick, Culver City, Calif., assignor to
Holophane Company, Inc., New York, N.Y.

Filed Oct. 24, 1969, Ser. No. 19,707

Term of patent 14 years

Int. Cl. D26—02

U.S. Cl. D48—4

FIG. 1

FIG. 2

FIG. 1 is a front perspective view of the luminaire embodying my new design;

FIG. 2 is a rear perspective view thereof.

The side not appearing in the drawings has same design appearance as side shown.

I claim:

The ornamental design for a luminaire, substantially as shown and described.
